UNITED STATES PATENT OFFICE.

LE GRAND PARISH, OF NEW YORK, N. Y.

LOCOMOTIVE-FIRE-BOX CONSTRUCTION.

1,089,666.

Specification of Letters Patent. Patented Mar. 10, 1914.

Application filed March 19, 1913. Serial No. 755,419.

To all whom it may concern:

Be it known that I, LE GRAND PARISH, a citizen of the United States, residing at New York, in the county of New York and 5 State of New York, have invented certain new and useful Improvements in Locomotive-Fire-Box Construction, of which the following is a specification.

This invention relates to the provision of 10 an improved arrangement of circulating tubes in a locomotive fire-box whereby the circulation between the different parts of the water walls of the fire-box is greatly increased in volume, such arrangement co- 15 operating with means whereby the rapidity of the flow of the water circulating through the tubes is increased and is even and uninterrupted in character. Such arrangement of parts is primarily intended to obtain 20 greater efficiency of the fire-box, particularly with reference to the fuel consumed. A further object of the invention resides in so constructing the parts, that they may be readily applied to locomotives of standard 25 construction and may be easily removed for purposes of repair or cleaning. My invention further contemplates the provision of tubes having the advantages and functional 30 characteristics described but which do not interfere with insertion and removal of the arch bricks supported on said tubes, nor 35 with the inspection and repair of the stay-bolts, flue sheet or flues.

These, together with such other objects as 40 may hereinafter appear or are incident to my invention, I attain by means of a construction which I have illustrated in preferred form in the accompanying drawings, 45 wherein—

Figure 1 is a longitudinal section through 50 a locomotive fire-box illustrating the application of my invention thereto; Fig. 2 is an end elevation of the fire-box; and Fig. 3 is a plan view of a detail of the invention.

On inspection of the drawings, particularly Fig. 1 thereof, it will be seen that the fire-box is of standard construction and comprises an inner fire-box composed of a tube sheet 1, side sheets 2, a back sheet 3, a crown sheet 4, and an outside fire-box composed of a throat sheet 1^a, side sheets 2^a, a back sheet 3^a and a cover or top sheet 4^a. The water spaces at the front, sides and rear of the fire box are closed by the usual mud ring. 5 The back sheets are connected together by the stay-bolts 6, while the cover and crown

sheets are connected by the radial stay-bolts 7. In the front of the fire-box is the usual flue sheet 13 in which the rear ends of the flues 12 are fastened.

Referring now to those features of my invention which are departures from the usual construction, it will be noted that I provide two rows of tubes 8 and 8^a connecting the front and rear water spaces and inclining upwardly from the front to the rear. The tubes 8^a are circulation tubes and the lower tubes serve as circulation tubes and also support the arch bricks 9 in such manner that the gases in the fire-box do not come directly in contact with the relatively cool surfaces of the tubes 8^a so that the combustion of said gases is not retarded. There are preferably four tubes to each row, and the tubes of one row are located directly below, 70 that is, in substantial alinement with the tubes of the other. This construction will be clear from inspection of Fig. 2 which is an end elevation of half of the fire box. The chief object in providing two rows of 75 tubes is to increase the amount of circulation between the different parts of the water spaces, and in order to secure a more rapid and uninterrupted flow through the tubes, I provide the following structure which 80 operates with said tubes in securing the desired results.

Arranged in the rear water space and detachably secured to the vertical pairs of tubes of the upper and lower rows of tubes 90 are four delivery tubes 14 which are adapted to be inserted and removed through openings in the back sheet 3^a and are provided with flanged cover plates 15 adapted to cover said openings and be secured to the sheet 95 3^a by means of studs 15^a and the stay bolts 6^a. The delivery tube castings each have a passage 14^a which opens into a larger passage 14^b. A tube of lower row 8 communicates with each passage 14^a and a tube of 100 the upper row 8^a communicates with the passage 14^b, the capacity of said latter passage being substantially that of two tubes. The delivery tubes extend upwardly and the ends thereof lie substantially at the level 105 of the normal water line of the fire-box. The currents of water and steam which are caused by the action of the heat in the fire-box to flow upwardly and rearwardly through the tubes are not discharged into 110 the rear wall space but are delivered in the space above the crown sheet and are there-

- 2
- fore not impeded or obstructed by the volume of water normally lying in the rear water space above the points at which the tubes 8 and 8^a communicate therewith.
- 5 Greater rapidity and continuity of the flow through the tubes is thus obtained, and this advantage in connection with the greater volume of circulation obtained by the provision of the two sets of tubes tends to lend 10 effectiveness to the fire-box without increasing the amount of fuel consumed. By making the passage 14^b of larger capacity than the passage 14^a, retarding of the flow through the delivery tubes is prevented.
- 15 Access is had to the rearward portions of the tubes by means of the wash-out plugs 10 and 10^a which are threaded into the delivery tube castings, while access is had to forward portions by means of the plugs 11 20 threaded into the throat sheet 1^a. The plugs 10 are provided with ports forming substantially a continuation of the passage 14^a and are also cut away so as not to interfere with the flow from the upper tubes. The plugs 10^a are similarly cut away so as to not interfere 25 with the flow through the lower tubes. The brick arch is preferably carried on the lower set of tubes.
- I claim:—
- 30 1. A locomotive fire-box comprising in combination with water walls, a pair of circulating tubes connecting the water walls, a delivery member extending upward from one water space to another and having a passage communicating with the discharge 35 ends of the circulating tubes, and means for detachably connecting the tubes and the delivery member, said passage being of larger capacity than that of a tube.
2. A locomotive fire-box comprising in 40 combination with water walls, a pair of circulating tubes communicating with a water wall, and a common delivery member communicating with the discharge ends of the tubes and extending toward the normal 45 steam space.
3. A locomotive fire-box comprising in combination with water walls and circulating tubes, a discharge or delivery member located in one of the water walls and common to a plurality of the tubes and extending upward from the discharge ends thereof to the normal steam space.
- In testimony whereof I have hereunto signed my name in the presence of the two 50 55 subscribed witnesses.
- LE GRAND PARISH.
